IGNITION BREAKER MOUNTING

Carl V. Chermendy and Waldemar H. Borchelt,
Grand Rapids, Mich.

Application September 25, 1952, Serial No. 311,516

5 Claims. (Cl. 200—30)

1

This invention relates in general to an ignition breaker mounting and is more particularly described as a rotatable mounting for a movable spark advance type of ignition breaker. In ignition breaker mountings of this kind, it is customary to mount the movable parts close together upon correspondingly fitted metal elements. In ignition breakers, this practice becomes extremely detrimental as the breakers become used and worn since the friction of one metal part upon the other produces objectionable wearing and soon the movable parts are so worn that the ignition parts are not in the alignment for which they are intended. This results in the wider separation of the ignition points or a to and fro weaving motion which produces a variation in the engagement of the ignition cam and this causes pitting and burning of the ignition points or contacts and sometimes resulting in oxidation and bouncing of the points which may be extremely objectionable.

An important object of the invention is therefore in the provision of a rotatable mounting for an ignition breaker in which relatively rotatable parts are provided of different materials particularly at the points where they bear upon each other, one of the materials being non-metallic and preferably of a plastic composition commonly known as nylon or a similar wear resistant plastic having the same characteristics.

A further object of the invention is to provide a nylon ring seated between two parts of an assembled ignition breaker mounting in such a manner that the nylon ring is protected by metal parts on opposite sides thereof, but the contact between the metal parts is upon the nylon ring and not upon similar wearing parts of metal.

A still further object of the invention is to provide a new and improved ignition breaker assembly mounting adapted to be used for ignition breakers of all kinds and to be used in connection with automatic spark advance tubes of installation.

Other objects of the invention will appear in the specification and will be apparent from the accompanying drawings, in which,

Fig. 1 is a plan view of an ignition breaker mounting in accordance with this invention and showing a conventional ignition circuit breaker on top thereof.

Fig. 2 is an exploded perspective view showing the parts of the breaker mounting in section; and

Fig. 3 is a sectional view of the circuit breaker parts in assembled relation.

A circuit breaker mounting of this kind is 55

2

particularly designed and intended for a movable spark advance type of ignition breakers which usually has a relatively fixed part and another plate movable with respect to the fixed part upon which the circuit breaker is mounted. The movable plate is then rotated in one direction or another depending upon whether the spark advance is to the right or to the left and thus varying the position of the breaker itself with respect to the cam which rotates within the breaker mounting.

Referring now more particularly to the drawings, an ignition breaker 10 of any type either of a new construction or of a conventional type as shown in Fig. 1 has a movable member 12 mounted for rotation about a post 14 with a spring 16 tending to press the outer end of the movable arm so that its contact 18 makes a flat engagement with a relatively fixed contact 20. Mounted on the member 12 is a projection 22 preferably of fibrous material adapted to be engaged by a cam projection 24 of a rotatable cam 26.

Various types of ignition breakers are commonly used for different ignition breaker systems used principally upon the ignition systems of different automobiles and the exact construction of the ignition breaker has no particular part in this invention since all ignition breakers of this type are subject to the same objection, that is, that they will wear unduly if the ignition breakers are mounted upon the conventional type of mountings having metal to metal contacts of the parts.

In the present invention, the ignition breaker is mounted upon a top plate 30 which preferably has a flat face on one side, a central opening 32 and an annular flat projection 34 on the other or under side which has a shoulder 36 spaced from the inner periphery and a shoulder 38 spaced from the outer periphery of the plate.

A bottom plate 40 of slightly larger diameter than the top plate has a flat surface on one side and an annular projection or rib 42 surrounding the central perforation 44 thereon on the other side. This annular rib 42 is of a width to fit the space upon the top plate between the inner periphery thereof and the shoulder 36 of its annular projection, the openings 32 and 44 of the top and bottom plates respectively being of the same diameter and adapted to fit closely together. In order to attach these plates together, one of the plates as the top plate has threaded openings 46 into which small screws 48 are inserted through appropriate openings 50 in the

bottom plate so that upon drawing the screws together more or less tightly, they will draw the plates together.

This construction of the top and bottom plates provides an annular recess between the two plates when they are fastened together, the recess extending from the outer shoulder 38 of the annular flat projection to the outer peripheries of the plates and of the thickness of the flat projection 34 such that a flat mounting ring 52 of the proper diameter may be inserted therein. This ring is composed of a non-metallic fibrous or plastic material resistant to wear such, for example, as a plastic commonly known as nylon which has a flat portion fitting closely between the upper and lower plates at their outer edges but permitting a free and relative movement between the two plates fastened together and the nylon ring 52. At the outer edge of this ring and projecting therefrom at the outer side around the top plate are ears 54, 56 and 58 formed integrally with the ring and usually having perforations 60 therethrough. The projections of this nylon ring are preferably flat and the outside diameter of this ring is substantially the same as that of the bottom plate with the top plate 30 movable within the projections of the nylon ring.

In assembling this construction, the mounting ring 52 is placed between the top and bottom plates 30 and 40 before they are secured together by the screws 48 and it is seated within the space provided for it where it makes a continuous and substantial contact with both of the mounting plates throughout their entire outer periphery.

To disassemble the mounting, the screws 48 are loosened and withdrawn and the parts can be easily taken apart for removal, replacement or repair of any of these elements. In order to apply a new breaker arm or a new ignition breaker, it may be more simple to remove the top plate 30 with one ignition breaker mounted thereon and to substitute therefor another similar top plate with another ignition breaker thereon.

This mounting assembly may be secured in place surrounding a central cam by the perforated ears 54, 56 and 58 in any suitable and well known manner and for advancing and retarding the spark, the entire mounting may be moved by an arm 62 attached by a suitable pivot 64 to the top plate and extending between any two of the projecting ears 56 and 58. This arm is moved endwise in either direction depending upon the direction necessary to correspondingly advance or retard the spark in a well known manner.

With this construction, the nylon mounting ring 52 which is very tough and resistant to wear, holds the mounting plates at their peripheries relatively rigid and out of moving contact with each other or with any other metal part so that the entire mounting assembly is substantially free from wear and thereby retaining the alignment of any ignition breaker mounted upon the top plate so that there is no uneven movement of

the ignition breaker mounting because of the minimum wear and no variation of the ignition points caused by continued use. The mounting ring 52 is easily replaced and there is no wear upon the metal plates because they do not come in wearing contact with each other.

While a preferred construction of the invention has been described in some detail, it should be regarded as an illustration or example rather than as a limitation or restriction of the invention, since various changes in the construction, combination and arrangement of the parts may be made without departing from the spirit and scope of the invention.

We claim:

1. A mounting for ignition breakers comprising a top plate and a bottom plate, the plates having cooperating surfaces to provide an outer peripheral recess between them, a mounting ring seated in the recess between the parts at the periphery thereof, the two plates being of metal and the mounting ring being of a wear resistant fibrous material, and means for securing the plates together with the mounting ring therebetween.

2. A mounting in accordance with claim 1, in which the two plates are of metal and the mounting ring is a wear resistant material such as nylon relatively movable with respect to the plates.

3. A mounting in accordance with claim 2, in which the mounting ring is of wear resistant fibrous material having a plurality of integral ears extending outwardly at one side of the ring at the periphery thereof and receiving the top plate within the ears.

4. A mounting in accordance with claim 3, in which the integral ears of the mounting ring are provided with perforations for attaching the ring to a suitable support so that the plates may be moved rotatably with respect to the ring.

5. A mounting for ignition breakers comprising a top plate and a bottom plate, the plates having projections from their adjacent surfaces when placed together to provide a peripheral groove between them and each having a central perforation of the same diameter, a mounting ring seated in the recess between the parts at the periphery thereof and having integral ears extending outwardly therefrom projecting beyond the periphery of the top plate and having perforations therein for securing the ring in a fixed position, an ignition breaker seated on the top plate and having a projection for engaging a cam rotatable in the central recess of the plate, means for securing the plates together with the mounting ring rotatable with respect thereto, and means engaging one of the plates for moving it relatively to the said mounting ring for advancing and retarding the ignition breaker relative to the operating cam.
